UNITED STATES PATENT OFFICE.

VIRGIL A. KEMPER, OF KANSAS CITY, MISSOURI.

INKING ATTACHMENT FOR TYPE-WRITERS.

1,004,175.

Specification of Letters Patent. Patented Sept. 26, 1911.

Application filed February 13, 1911. Serial No. 608,218.

To all whom it may concern:

Be it known that I, VIRGIL A. KEMPER, a citizen of the United States, residing at Kansas City, in the county of Jackson and State of Missouri, have invented new and useful Improvements in Inking Attachments for Type-Writers, of which the following is a specification.

My invention relates to an attachment for typewriters, and more particularly to a ribbonless inking device therefor.

The principal object of my invention is to provide a device whereby the ribbons now in use are done completely away with, the ink being supplied to the type faces by means of a sponge or other absorbent substance placed in such position as to cause the type bars to barely graze the ink wetted surface on their way to the platen roller.

Another object of my invention is to provide such a device as the above which may be easily applied to any of the machines now in use and which may be adjusted in any desired position thereon in order to provide the proper contact between the type faces and the inking surface.

Another object of my invention is to provide a device of the above nature the inking member of which may be easily and quickly removed in order to be reinked, or for any other desired purpose.

With the foregoing and other objects in view my invention consists in such details of construction and in the arrangement and combination of parts as will be hereinafter more fully described and specifically pointed out in the appended claims.

In describing my invention in detail reference will be had to the accompanying drawings wherein like characters denote like or corresponding parts throughout the several views, and in which:

Figure 1 is a view of my invention partly in elevation, and partly in section as seen when sitting directly in front of a typewriter (not shown). Fig. 2 is a view in elevation taken at right angles to Fig. 1. Fig. 3 is a top plan view of the device. Fig. 4 is a detailed view of the spring adjusting mechanism, and Fig. 5 is a detailed view of the ball or socket construction whereby a high degree of adjustment may be secured.

In the drawings the numeral 1 represents a portion of a typewriter frame. It will be understood that my attachment can be connected to any part of the frame, provided it

is attached in some position as to permit the inking surface to be so adjusted as to cause the type faces to brush by said surface when the keys of the machine are touched. In carrying my invention into practice an arm or standard is connected to the frame in any suitable manner, bolts being the fastening means which I disclose in the drawings. This standard may be solid if preferred or may be made in two parts 2 and 3 as illustrated, this form being shown merely for convenience and simplicity in the construction of the ball and socket joints hereinafter described. The two portions of the standard may be connected together by means of rivets or other fastening devices 4. The upper end of one arm is enlarged and perforated as at 5, the upper end of the other part of the standard being also enlarged 60 and having a recess formed therein in the shape of a hemisphere as shown at 6. A thumb screw 7 passes through one side of the recessed end and is adapted to engage the ball 8. Connected to the ball is an arm 9. This arm may be connected to the ball in any suitable manner, but a bolt and nut connection such as that shown at 10 permits a higher degree of adjustment to be attained. On the swinging end of the arm 9 is connected a socket 11 by means of a bolt and nut joint 12. This socket is internally screw threaded and is adapted to receive a member 13, which forms a pass in which may be cemented or otherwise attached thereto, a sponge 14 or similar device of any other suitable absorbent material.

Connected to the frame of the typewriter is a plate 15, which carries a bracket 16 thereon, which bracket has an outwardly turned arm having a perforation in which a rod 17 is slideable. The bracket 16 is disposed at such an angle on the plate 15 as to direct the rod 17 at the proper inclination toward the swinging end of the arm 9. One end of the rod 17 is screw threaded as at 18, a thumb nut 19 being mounted on said screw threaded end so disposed as to be adapted to come in contact with the outwardly turned arm of the bracket 16. The other end of the rod 17 has connected to it a tension spring 18, which spring is in turn connected to the swinging end of the arm 9 by being fastened under the nut 12 before mentioned. It will be seen that the sponge 110 or inking surface may thus be accurately adjusted to a high degree. Not only is it ad-

2
justable through the medium of the ball and socket joint but a very nice adjustment with relation to the path of the type bars may be obtained by use of the thumb nut 19. In spite of its flexibility of adjustment the device is held perfectly stationary by means of the thumb screw 7, which engages the ball 8 as before set forth.

The device must be adjusted of course with particular view to each machine upon which it may be used, but the foregoing construction enables it to be readily adapted to any machine now upon the market. After once being adjusted it will be held stationary and need not be moved unless desired, but at the same time it can be easily and quickly folded down out of the way if it is desired to do so.

I desire it to be understood that slight changes in the construction and in the arrangement and combination of the various parts may be resorted to without departing from the spirit of my invention, provided such changes fall within the scope of the appended claims.

Having thus fully described my invention, what I claim as new and desire to secure by Letters Patent, is:—

1. An attachment for typewriters comprising a standard, an arm universally connected thereto, means for holding said arm rigid with relation to said standard, an absorbent material extending from said arm.

2. An inking attachment comprising a standard, an arm adjustably connected thereto, absorbent material carried by said arm, and means for adjusting the end of said arm independently of its adjustable connection to said standard.

3. An attachment for typewriters com-

prising a standard, an arm carried thereby, inking material carried by the end of said arm, a plate on the typewriter frame spaced from said standard, a rod carried by said plate and connected to said arm, and means for adjusting said rod whereby the end of said arm may also be adjusted. 45

4. An attachment for typewriters comprising a standard, an arm carried thereby, inking material carried by said arm, and means for adjusting the end of said arm independently of its adjustable connection to said standard, said means comprising a plate spaced from said standard, a rod slidably mounted with relation to said plate, a spring connecting said rod and the end of said arm, and means for sliding said rod with relation to said plate whereby the end of said arm may be adjusted. 50

5. In a device of the character described, a standard comprising two connected together plates, the upper ends of said plates formed into a socket, a ball in said socket, an arm connected to said ball, a socket carried by said arm, ink saturated material carried by said socket, and means for laterally adjusting the swinging end of said arm. 60

6. An attachment for typewriters comprising a standard, a socket in the upper end of said standard, a set screw extending into said socket, a ball in said socket, an arm connected to said ball, a socket carried by an end of said arm, a bracket, a rod adjustably held by said bracket, a spring connecting said rod and said arm and means for regulating the tension of said spring. 70 75
